UNITED STATES PATENT OFFICE.

JOHN F. BROWN, OF CHICAGO, ILLINOIS, ASSIGNOR TO ALBERT R. BAKER,
OF INDIANAPOLIS, INDIANA.

ORDER-HOLDER.

SPECIFICATION forming part of Letters Patent No. 436,396, dated September 16, 1890.

Application filed April 25, 1890. Serial No. 349,495. (No model.)

To all whom it may concern:

Be it known that I, JOHN F. BROWN, a citizen of the United States, residing in Chicago, in the county of Cook and State of Illinois, 5 have invented a new and useful Improvement in Order-Holders, of which the following is a specification.

This invention relates to the construction of clamping-springs and the method of securing them in place upon order-holders.

As described in a former application filed by me, I employ in the present case two or more short clamping-springs, two inches or so in length, instead of the long single spring 15 employed previous to my said former invention. These springs, inasmuch as there is no canvas or other connection between the two halves of the holder, must be secured to the narrow boards of the holder with considerable firmness, because if they slip off or become loose there is nothing to hold the two halves of the holder together. The means of securing the springs upon the holder which I employ consists of indentations in the springs 25 whereby projections or points upon the inner surface of the springs are formed and caused to engage with corresponding recesses in the narrow boards of the holder. These recesses I find, however, are liable to tear out, and 30 hence I provide the narrow boards, at the points where these recesses are made, with metallic strips with which the projections formed by the indentations will engage. These metal strips are let into the paste- 35 board of the narrow boards of the holder and covered by the canvas thereof so that they cannot escape. These and other details of my invention are fully set forth in the accompanying drawings, wherein—

40 Figure 1 is a plan of my improved order-holder. Fig. 2 is a plan of one of the narrow boards with the canvas cover removed. Fig. 3 shows the same board with the metal holding-strips in place. Fig. 4 is an enlarged section upon the line 4 4 of Fig. 1.

45 In said drawings, A a represent the wide or large boards of the holder, and B b the narrow. Each of the wide boards is united to one of the narrow boards by a canvas 50 cover c, such canvas forming the hinge uniting

the wide and narrow boards, as shown at d. The narrow boards are formed of two layers of pasteboard B b. The outer board B of the narrow part is provided with slots E, having lateral enlargements e. In the body of these 55 slots I insert a narrow metal strip F, which substantially fills the slot and is covered and held in place by the canvas cover.

G G are the clamping-springs, of which I use preferably three upon wide holders and 60 two upon narrow ones. These springs are indented upon each side, as shown at g, thereby forming upon their inner surfaces projecting points h, and these indentations are located so that the points h will enter lateral 65 enlargements e of the slots in the pasteboard with the protruding points of the springs engaging with the bars F. It will be seen from this construction that any effort to draw off the springs or to pull the boards out from 70 their embrace will be resisted by the engagement of the metal parts h and F. I thus avoid the danger, which would exist if the projecting points h were not engaged by a metal stay, of their forcing their way through 75 the soft material of the holder and thus becoming detached.

I claim—

1. The combination, in an order-holder, of 80 springs having inward projections, in combination with the boards embraced by such springs, the latter being provided with metal bars engaging said projections upon the springs, substantially as set forth.

2. In an order-holder, the combination of 85 the clamping-springs having inward projections, with the narrow boards made in two parts, with the outer part slotted, and metallic bars or stays inserted in said slots, substantially as set forth.

3. The combination of the clamping-springs having the inward projections h with the narrow boards B b, the outer portions of said boards being slotted, as at E e, and the metallic bars inserted in the body of the slots, 95 substantially as set forth.

JOHN F. BROWN.
